DEVICE FOR WINDING YARN AND THE LIKE

Filed Nov. 10, 1927

Fig. 1.

UNITED STATES PATENT OFFICE.

ALBERT B. COLLINGBOURNE, OF ELGIN, ILLINOIS, ASSIGNOR TO COLLINGBOURNE MILLS, INC., OF ELGIN, ILLINOIS, A CORPORATION OF ILLINOIS.

DEVICE FOR WINDING YARN AND THE LIKE.

Application filed November 10, 1927. Serial No. 232,345.

This invention relates to improvements in spindles for holding the cores upon which yarn, thread and the like may be wound while the spindle is being rotated.

5 The object of the invention is to produce a spindle capable of efficiently holding a novel type of core for receiving the yarn, by the use of which I am enabled to eliminate all movable, radially extending friction devices 10 for engaging the inner surfaces of the tubular or other shaped cores now in use.

The improved spindle head is exceedingly simple in construction, efficient for its intended purpose of firmly holding cores while yarn 15 is being wound thereon, has no moving parts to get out of order and is economical in use in that it is adapted to hold a novel, inexpensive type of core not heretofore known and which other spindle heads have been incapable of 20 holding for the purpose intended.

In the drawings:

Figure 1 is a side elevation of a spindle embodying my invention and of a core in position in the spindle head, the wound yarn 25 thereon being indicated in dotted lines.

Figure 2 is a top plan view of the spindle head with a core in position therein, the wound yarn being indicated in dotted lines.

Figure 3 is a sectional view taken in the 30 plane of line 3, 3 of Figure 1, but omitting the lines indicating the yarn.

Figure 4 is a fragmentary, vertical sectional view taken in the plane of the line 4, 4 of Figure 3, slightly enlarged, and with the core 35 eliminated.

Figure 5 is a perspective view of the preferred form of core intended to be used with the spindle.

Figure 6 is a side elevation of a modified 40 form of spindle embodying my invention.

Figure 7 is a sectional view taken in the plane of the line 7, 7 of Figure 6, looking in the direction indicated by arrows.

In that embodiment of my invention, which 45 I have chosen to illustrate in the drawings, 10 is the spindle shaft carrying a head 11 which may be connected thereto in any desired manner or may be integral therewith. The head 11 may be of any desired size both as to length 50 and diameter. As shown in the drawings, it is round in cross section but it may be square, rectangular, oval or of any desired form.

In that form shown in Figures 1 to 4, inclusive, the spindle head 11 is provided with

two slots 12 and 13, each extending across the 55 entire head 11 at right angles to each other and from the top of the head to a point near the lower end. These slots divide the major portion of the head into four segmental sections 14, 15, 16 and 17, respectively, held together by the unslotted portion near the bottom of the head. The width of the slots is such as to accommodate a piece of card-board 60 of desired thickness.

In one of the longitudinal surfaces of the 65 segment 14, facing the slot 12, a relatively long, narrow recess 18 is provided for the reception of a flat spring 19, which may be held therein in any desired manner. A similar recess 20 for the reception of a spring 21 70 is provided in one longitudinal face of segment 16 facing the other slot 13. The exact location of spring 19 and 21 is immaterial so long as at least one spring is provided for each of the slots 12 and 13. 75

Referring now to Figure 5, it will be seen that one form of core intended to be used with my improved spindle comprises two flat pieces of card-board or the like 22, 23, which may be square, rectangular or of any desired 80 form, and each provided with a slit midway between its side edges, said slit being of a width equal to the thickness of the card-board and extending from the center to either the top or bottom edge of the blank. The slits are 85 indicated at 24 and 25, respectively. The card-board blanks 22, 23 are assembled as shown in Figure 5, with the edges of the slot 25 of the blank 23 engaging the unslit portion of the blank 22, and the edges of the slot 24 of 90 the blank 22 engaging the unslit portion of the blank 23. When thus assembled the core may be inserted into the slots 12 and 13 of the spindle head 11 from the top of the spindle and pressed downwardly to a desired extent. 95

The springs 19 and 21 in their respective slots will frictionally engage the blanks 22 and 23 to firmly hold the same during the winding operation while permitting the core and the yarn wound thereon to be removed when desired. 100

The width of the blanks 22, 23, is such that the edges extend beyond the outer surfaces of the segments 14, 15, 16, 17, to a desired degree, to permit the yarn to be wound to overlap the ends or what may be called the top and bottom of the core. The finished article will 105 be substantially cube-like in form when

wound on a core such as illustrated in Figure 5.

To make a substantially flat package of yarn, one blank only may be used as a core and inserted in one of the slots of the spindle head. For this purpose a small sized spindle head or an oval shaped spindle is preferably used. It will also be obvious that the slots 12 and 13 need not always be at right angles 10 to each other, but the form and arrangement shown herein is recommended, to produce a popular shape of package.

Figures 6 and 7 illustrate a modified form of spindle which, when assembled, is practically identical with the form shown in Figures 1 to 4. In the manufacture of the modified form, the shaft and head are made in segmental form and the segments 26, 27, 28 and 29 are held together by a collar 30 which is 20 maintained in position by a set screw 31. The modified form of spindle is provided with springs indicated by the same numerals as those applied to the same parts in Figure 1 to 4, inclusive, and the spindle is adapted 25 to be used as heretofore explained with reference to said figures.

Modifications may be made without departing from the scope of my invention and I do not desire to be limited to the precise 30 forms described, except as set forth in the appended claims.

I claim as my invention:

1. A device for winding yarn, comprising a spindle and a spindle head connected thereto, said head being provided with a longitudinally arranged slot extending across the head and inwardly from the top surface thereof, and a flat spring in the slot, the longitudinal walls of the slot and the said spring being adapted to frictionally engage the surface 40

of a card-board blank to be inserted therebetween.

2. A device for winding yarn, comprising a spindle and a spindle head connected thereto, the major portion of the head being divided into sections by slots angularly disposed with respect to each other extending from side to side and from the top of the head to a point near the lower end, and flat springs 45 in the slots, the longitudinal walls of the slots and the springs being adapted to frictionally engage the surfaces of the card-board core to be inserted therebetween.

3. In a device for winding yarn and the like, a spindle head comprising four segmental sections connected together at their lower ends, springs between the sections, the proximate walls of the segmental sections being adapted to frictionally engage a card-board core to be inserted therebetween. 55

4. A device for winding yarns, comprising an elongated solid spindle head provided with a plurality of communicating slots disposed at right angles to each other, each of said slots extending entirely across the head 65 from side to side thereof and downwardly from the top surface of the head, the slots being of substantially the same length as the cardboard core, having radially extending wings, intended to be seated therein with its radial wings extending beyond the outer surfaces of the head, and the proximate walls of the slots being sufficiently close together to frictionally engage the surfaces of the radially extending wings of the core. 70

In testimony, that I claim the foregoing as my invention I affix my signature this 8th day of November, 1927.

ALBERT B. COLLINGBOURNE.
